ATTYS

UNITED STATES PATENT OFFICE.

FRANZ LUDWIG PIRO, OF RÖDELHEIM, GERMANY.

STICKING-PLASTER.

No. 832,621.

Specification of Letters Patent.

Patented Oct. 9, 1906.

Application filed December 20, 1905. Serial No. 292,650.

To all whom it may concern:

Be it known that I, FRANZ LUDWIG PIRO, a subject of the German Emperor, and a resident of Rödelheim, near Frankfort-on-the-5 Main, Germany, have invented a certain new and useful Improvement in Sticking-Plaster, of which the following is a specification.

This invention relates to a plaster the novelty of which resides in the feature that the various disks or sheets of plaster material consist of a number of leaves or petals radiating from a core or heart. By distributing the disk or sheet into these specially-formed 10 patches or wafers, which can all be secured at a very narrow part, it is rendered possible to readily separate each patch individually, it being only necessary to grip the same lightly, so that neither it nor the adjacent 15 pieces are soiled. So that one may have at hand various sizes of patches, according to the intended use of the same, the various disks are made of various diameters and superposed with each disk above the next 20 larger one. The disks are secured to each other only at the center or heart portions. In order that the one disk will not cover that below, which would render the pieces less accessible, the various disks are arranged in 25 staggered order, so that the petals on one disk lie between the petals on the disk beneath. As the disks of smallest diameter are on top, the whole arrangement resembles that of a flower.

30 Various embodiments of the invention are illustrated in the accompanying drawings.

Figures 1, 2, and 3 show three different forms of disks. Fig. 4 is a plan and Fig. 5 an end view showing the arrangement of super-40 posed disks.

The plaster-disk shown in Fig. 1 comprises petals *b*, cut or stamped out, which are broadened toward their free ends, but taper toward the central core *a'*, which joins together all the petals.

45 In Fig. 2 the patches *b'* are shown stamped out in substantially circular form and are joined to the core *a'* only by small tendinous pieces, while the core itself is the same size 50 as the patches *b'* and can also be used.

In Fig. 3 the patches *b* are shown stamped out in spear-shaped form, so that they are curved almost equally at both ends, whereby it is likewise possible to secure the same to the core *a* at so narrow a part that it is 55 easily possible to separate the various patches.

Fig. 4 shows five such disks of the kind shown in Fig. 1, which are held together only at their cores *a*, Fig. 5, by an adhesive carried by intermediate layers. The patches *b* of the various layers are superposed in staggered order, so that each patch can be readily seized at its free outer end and be readily pulled or plucked from the core. 65

Having described my invention, what I claim, and desire to secure by Letters Patent of the United States, is—

1. A plaster made of a single piece of material and comprising a core and radial petal-like patches connected to said core by narrow strips whereby said petals may be easily detached from the core. 70

2. A plaster consisting of an integral piece of material having portions cut therefrom so as to leave a center core and radial petal-like patches connected to said core by narrow strips whereby said petals may be easily detached from the core, said core and patches being coated with an adhesive. 75

3. A plaster comprising a plurality of superposed disks connected together, each disk consisting of an integral piece of material having portions cut therefrom so as to leave a center core and radial petal-like patches connected to said core by narrow strips so that said patches may be easily detached from the core, an adhesive coating for said core and patches the patches of one disk lying between the patches of the disk beneath. 85

In testimony whereof I have signed my name to this specification in the presence of two subscribing witnesses.

FRANZ LUDWIG PIRO.
